UNITED STATES PATENT OFFICE.

EDWARD A. RASBRIDGE, OF SCRANTON, PENNSYLVANIA.

SAFETY-CAP FOR INFLATION-VALVES OF PNEUMATIC TIRES.

1,161,728.

Specification of Letters Patent.

Patented Nov. 23, 1915.

Application filed May 10, 1915. Serial No. 27,103.

To all whom it may concern:

Be it known that I, EDWARD A. RASBRIDGE, a citizen of the United States, residing at Scranton, in the county of Lackawanna and State of Pennsylvania, have invented certain new and useful Improvements in Safety-Caps for Inflation-Valves of Pneumatic Tires; and I hereby declare that the following is a full, clear, and exact description thereof, reference being had to the accompanying drawings, which form part of this specification.

This invention relates to inflation valves for pneumatic tires, and more particularly to safety devices for closing the bore of the valve-stem or nozzle through which the pneumatic tube is inflated or deflated, so as to prevent the escape of air in case of leakage through the usual check-valve controlling the air vent.

The primary object of the invention is to provide simple, efficient and inexpensive means for effecting a perfect closure of the air vent to prevent the escape of air, together with means for unseating the check-valve to permit the air to escape for the purpose of deflating the pneumatic tube, and which means are not liable to become lost or mislaid in deflating the tube.

The invention will first be hereinafter more particularly described, with reference to the accompanying drawings, which are to be taken as a part of this specification, and then pointed out in the claims at the end of the description.

In said drawings, Figure 1 is a vertical sectional elevation of a device embodying my invention, showing the reversible cap attached to effect a closure of the air vent; Fig. 2 is a similar view showing the cap in side elevation and in reversed position from that shown in Fig. 1 for the purpose of holding the check-valve open for deflating the inner tube; Fig. 3 is a perspective view of the reversible cap; Fig. 4 is a bottom plan view of the same; and Fig. 5 is a vertical sectional view of the device used within the socket of the reversible cap for closing the air vent.

Referring to said drawings, in which the same letters of reference are used to denote corresponding parts in different views, the letter A may denote the valve body or stem of an ordinary inflation valve for pneumatic tires having an externally threaded end protruding through the rim of the wheel; said

end, in the form shown, having a reduced extension a , also externally threaded for the attachment thereto of a suitable closure or cap B. The cap B has at one end an interiorly threaded socket adapting it to be screwed upon the externally threaded portion a of the valve body or stem A, for the purpose of closing the air vent or bore of said body in which there is a valve stem C carrying at its inner end an ordinary inwardly opening valve (not shown) controlling the admission and escape of air through said bore, for the purpose of inflating or deflating the pneumatic or inflatable tube to which the valve is attached in the ordinary manner. Within the socket end of the cap B there is preferably a conical extension of the socket in reduced size adapted to receive a correspondingly shaped projection d on a valve member D which is seated on an annular shoulder at the base of said socket; said valve member having a lead or other soft metal gasket or washer d^1 thereon which is preferably of conical form and adapted to be seated against a correspondingly shaped or beveled end of the valve stem A when the latter is screwed into the socket of the cap, whereby the air vent through the valve-body or stem A is effectually closed and made perfectly air-tight to prevent the escape of air in case of leakage through the usual check valve within the stem or inflatable tube. The other end of the reversible cap B is formed with a projection d^2 , which is flattened on one or both sides thereof, as at d^3 , to provide an air vent between the flattened side or sides and the adjacent wall of the tubular stem into which it is screwed; said projection d^2 being threaded on opposite sides thereof, as at d^4 , to adapt it to be screwed into the interiorly threaded end of the valve body or stem A, for the purpose of engaging the end of the valve stem C and unseating the valve within the valve-body or inflatable tube.

I thus provide a very simple, efficient and inexpensive device which will prevent the escape of air from an inflatable tube in the event of leakage through the usual check-valve, and at the same time a simple and efficient means for unseating and opening the check-valve for the purpose of deflating the pneumatic tube by simply reversing the cap, such device being also adapted to enable the autoist to relieve the pressure within the inflated tube when desired by simply revers-

ing the cap, and in either case avoiding the liability of mislaying or losing the cap while waiting for the inflatable tube to vent; while in the reverse position very effectual means are provided for closing and sealing the air vent so as to prevent the escape of air should the usual check-valve fail to perform its usual functions.

Having thus described my invention, what 10 I claim as new and desire to secure by Letters Patent is:

1. In an inflation valve for pneumatic tires, the combination with a valve body having a longitudinal bore and threaded exteriorly at one end; of a safety cap having an interiorly threaded socket adapted to engage the threaded end of the valve body, a valve-member fitted in the lower end of said socket, and an annular soft metal gasket 20 surrounding the upper end of said valve-member and adapted to be engaged by the end of the valve body and effect an air-tight

closure of the bore therethrough when the cap is screwed thereon.

2. In an inflation valve for pneumatic 25 tires, the combination with a valve body having a longitudinal bore and threaded exteriorly at one end; of a safety cap having an interiorly threaded socket provided with a reduced tapered extension in its bottom, a 30 valve-member having a tapered shank engaging said tapered extension, and a soft metal gasket surrounding the upper end of said valve-member and adapted to effect an air-tight closure of the bore through the end 35 of the valve body when the cap is screwed thereon.

In testimony that I claim the foregoing as my own, I affix my signature in presence of two witnesses.

EDWARD A. RASBRIDGE.
